ANIMATED BOOKLET TOY

Nicolas Juan Gibelli, Buenos Aires, Argentina

Application September 9, 1950, Serial No. 183,940
In Argentina February 11, 1950

1 Claim. (Cl. 46—34)

1

This invention relates to an animated image foldable paper sheet book toy.

By means of this invention it is possible to obtain books and other toys of the same type, wherein one or more animated or movable images, in combination with complementary fixed images will form a picture representative of a given scene in which both the movable or partly movable images and the fixed images are located on different planes. A more real appearance is thus obtained due to the relief effect produced by the combined movable and fixed images arranged on different planes.

It is believed that the improvements of this invention constitute an advance in the art, since heretofore it has been possible to obtain books or the like containing animated pictures arranged on a single plane, or else in two or more planes, but in this case they are not movable. Thus, a combination of these two types of toys, generally used in illustrating children's stories, will be considerably more interesting as a result of the more real appearance thereof.

The invention comprises mainly a book or the like including a supporting body constituted by two plane sections arranged for holding so as to form a dihedral angle; one or more fixed images formed by cuts in one of said two plane sections spaced from one another, said fixed images being provided with round openings traversed by movable members supplementing the images by the protecting front portion thereof corresponding to the front of the toy, and connected to a foldable sliding actuating member connected to the rear face.

In order that the invention may be more clearly understood and readily carried out, a preferred embodiment thereof has been illustrated by way of example in the accompanying drawings, in which:

Fig. 1 is a part sectional general view of the front face of the toy.

Fig. 2 is a longitudinal sectional view of the toy shown in Fig. 1 along line 2—2 thereof.

Fig. 3 is a front detail of one of the parts of the assembly shown in Fig. 1; and

Fig. 4 is a schematic view of Fig. 2 in folded position.

The same reference characters are used to indicate like or corresponding parts or elements throughout the drawings.

As shown in the drawings, the invention is in the form of a book having generally two flat sections *a* and *a'* foldably connected to each

2

other at the folding line 1. Front and rear bristol board sheets 2 and 3 are joined together by means of small strips 4, and when folded together along line 1, provide the two book-like sections *a* and *a'*.

The sections of the front sheet 2 are formed with a series of cuts 5 so as to form separate relief images *b*, *c* and *d*, representing an animal holding a hammer, a working table and a further animal also holding a tool, respectively. Since the table *c* is formed only by side cuts and comprises a part of section *a* and a portion of section *a'*, upon folding the two sections in the manner shown in Fig. 4 it will remain horizontally on a plane parallel to the section *a'*; portion 6 forming the table leg will be vertically disposed with respect to section *a'*. Inasmuch as the two images representing the animals are joined to the horizontal section *a'*, they will be also vertically disposed with respect to the latter, as shown more clearly in Fig. 4.

Actually, the fixed images such as the working table *c* are formed in their entirety by means of said cuts 5, whereas the movable images such as those designated at *b* and *d* are formed partly by means of such cuts, using zones of the front sheet 2, and partly by additional pieces made with other pieces of bristol board or even using pieces completely separated from the sheet 2. Thus, body 7 and left arm 8 of the animal *b* which are fixed, are formed directly by cutting sheet 2, whereas head and cap 9 and right arm 10 which are movable, are constituted by independent pieces.

For the purpose of associating the fixed parts with the movable parts, the fixed parts are provided with rounded holes 11 engaged by connecting arms 12 having at one of the ends thereof the respective portions of the movable figures or images. Said arms 12, which are formed by narrow bristol board strips are capable of moving freely in said rounded holes, so as to cause the movement of the images associated therewith. The arms 12 remain concealed from the front sheet 2 of the book, see Figs. 1 and 3.

At the back of sheet 2, between the latter and the sheet 3, said arms 12 are connected with hand actuating means which is also located between the sheets 2 and 3. The hand actuating means may be of any suitable type, depending mainly on the requirements to be met by the construction of the books or the like and also by the construction, quantity and arrangement of the movable parts of the images. In the embodiment illustrated, the actuating means is con-

stituted by a control member *e* formed mainly by a sheet also made of bristol board and extending to both sections *a* and *a'*, as shown particularly in Figs. 1, 2 and 4. This member *e* provides a short hand actuating arm *13* extending outwardly of section *a'* through a slot *14* formed in the front sheet *2*. The main portion of member *e*, the general shape of which is shown in Figs. 1 and 3, will in practice form a right angle when the book is semi-folded to a similar angle, and inasmuch as it is held with a certain degree of freedom between the sheets *2* and *3*, it is capable of sliding between said sheets which will thus act as a guide therefor. When the spacing of the images from the front sheet *2* allow it, the member *e* provides separate parts for connection with the aforesaid connecting arms *12*. With regard to the image *b*, the member *e* provides a support *15* having a horizontal slot *16* in which the lower end of arm *12* is housed.

For operating the connecting arm *12* corresponding to the image of animal *d*, a support *17* is also formed by suitable cuts in the sheet body of member *e*, which is shown unfolded in Fig. 1 and provides a slot *18* in which the lower free end of arm *12* is inserted. This support system is preferably used for moving images or parts of images located at a considerable distance from one of the sections *a* or *a'* as in the embodiment illustrated.

It will be seen from the above that the operation of the combination as described above is simple and sure. By the rectilinear hand operation of member *e* by means of the outer arm *13* thereof as indicated by the arrows in Figs. 1 and 3, the member *e* will be moved from left to right and vice-versa, said movement being accompanied by that of the supports *15* and *17*. The rectilinear displacement of the supports *15* and *17* will cause, by combination with the action of the corresponding rounded holes *11* in which the connecting arms *12* are also inserted, the free angular movement of said arms, which is translated into a corresponding movement of the visible parts of the images, which, as mentioned

above, are connected to the arms *12* at the end opposite that at which they are connected with their respective supports.

It should be understood that in carrying out this invention, many changes, modifications and/or alterations will occur to those skilled in the art, without departing from the scope of the invention as clearly set forth in the appended claim.

10 I claim:

An animated image toy comprising front and rear parallel paper sheets connected together at opposite ends and foldable together at the middle thereof, a fixed figure struck from the front sheet and extending to the opposite side of the fold line but being connected to the front face sheet below the fold line and spaced therefrom whereby to extend vertically upon the sheets being folded, said fixed part having a pivot opening therein, a movable part having an operating arm extending through the pivot opening and depending therebelow, a slide operating member, slidably between the two sheets and having a handle portion accessible to the exterior of the front face sheet, said operating member having an inwardly struck portion and providing upon the sheets being folded, a vertical part spaced from the fold line and a horizontal part having a slot opening therein, said member operating on the movable part projecting through the slot opening of the struck portion of the operating member whereby as the operating member is moved by its handle, the movable part will be operated and will be retained with the fixed part at a considerable distance from the fold line.

NICOLAS JUAN GIBELLI.
